SENSITIVE CONDITION RESPONSIVE CONTROL SWITCH

John E. Lake, Schenectady, N. Y., assignor to
General Electric Company, a corporation of
New York

Application July 22, 1941, Serial No. 403,474

17 Claims. (Cl. 200—139)

The invention relates to electric switches and particularly to sensitive, condition responsive control switches for use in condition control systems or other similar circuit control service.

One of the principal objects is to provide an improved sensitive control switch unit adapted for automatic operation by a sensitive, condition responsive device having a relatively feeble operating force.

Another object is to render the sensitive control switch unit capable or reliably controlling the maximum amount of electrical energy in both making and breaking the circuit with a minimum amount of mechanical energy input from the sensitive, condition responsive switch operating device throughout a maximum number of circuit controlling operations.

A further object is to provide improved means for varying the differential of operation of the improved switch unit by the sensitive, condition responsive control device in closing and opening the circuit.

A still further object is to provide an improved form of sensitive temperature responsive operating mechanism for the switch.

More specific objects are to provide an improved anti-friction, automatic wear compensating, current conducting pivotal mounting for the movable parts of the switch unit, an improved anti-welding switch contact magnetic field structure and an improved self-regulating, resilient snap action operating mechanism for effecting the closing of the switch contacts with a substantially constant contact closing pressure resiliently applied normally to the contacting surfaces so as to reduce the tendency for welding to occur at high values of current due to bouncing, sliding, or increase of pressure between the contacts, and for separating the contacts with a slow motion, short hammer blow that is effective both in interrupting high values of alternating currents and in breaking any slight welding or sticking of the contacts that may have occurred. Provision also is made for obtaining an increased force from the operating device for breaking the switch contacts apart in case the initial slow motion short hammer blow should fail to break any weld between the contacts.

Further objects and advantages of the present invention will become evident from the following description of the accompanying drawings illustrating preferred embodiments of the invention and in which Fig. 1 is a top view partly in section of an improved sensitive, thermostatically

operated enclosed control switch with the enclosing cover removed; Fig. 2 is an end view from the left of the switch shown in Fig. 1 illustrating more clearly the improved switch differential regulating mechanism; Fig. 3 is a sectional view showing in detail the improved contact mounting and snap action operating structure of the enclosed sensitive control switch unit; Fig. 4 is a top view of the switch structure shown in Fig. 3 with the enclosing cover removed; Fig. 5 is an enlarged view partly in section of one of the spring pressed current conducting mounting pivots of the switch shown in Figs. 3 and 4; Fig. 6 is a sectional view of a modified form of enclosed sensitive switch unit of the double contact type for opening one circuit and closing another circuit with a slow motion snap action; and Fig. 7 is a top view of the double contact form of switch shown in Fig. 5 with the enclosing cover removed.

In the improved thermostatic switch of Figs. 1 and 2, the sensitive control switch unit 10 is provided with a removable dust-tight cover 10a, preferably of moulded insulating material, with a sliding operating pin 11, also of insulating material, extending therethrough. The improved construction of the enclosed switch unit 10 is shown in detail in Figs. 3 and 4. The switch unit 10 is mounted upon a bracket or plate 12 provided with suitably spaced holes for receiving the mounting bosses 14 and 15 projecting from the switch cover 10a with the operating pin 11 mounted in a slide bearing formed centrally in the boss 14 so as to extend through the mounting plate 12. The switch unit 10 is secured to the mounting bracket 12 by the mounting screws 16 and the bracket 12 is secured to a main base 18 by the screws 19 which are threaded into the ears 20 turned up from the edge of the plate 12. The main base 18 is provided with bent over side, top, and bottom walls 21, 22, and 23 for engaging with an outer enclosing cover (not shown) for the entire switch operating mechanism.

The switch mounting bracket or plate 12 has an upturned front portion 25 in which a clamping socket 26 is provided for the left-hand end of the temperature adjusting shaft 27 to which the right-hand end of the spirally formed, bimetallic, sensitive temperature responsive operating element 30 is firmly secured, preferably by welding. The right-hand end of the adjusting shaft 27 is removably mounted in a bearing 31 formed in the end of the enclosing tube or dry well 32 which is sealed into a threaded mount-

ing cap 34 so that the tube may be mounted in a tapped opening in the wall of a heating boiler, hot water tank, or any other fluid container and thereby render the sensitive thermostatic operating element 30 responsive to changes in a predetermined temperature condition.

The base 18 is provided with a specially formed annular mounting hub 35 having a cylindrical portion 36 removably and adjustably mounted in the open end of the tube 32 with a groove 37 in the outer surface thereof for receiving the end of the holding screw 38. Upon loosening the screw 38, the entire switch mechanism may be readily adjusted into any desired angular position or removed from the tube 32 for inspection, repair, or replacement.

The left-hand end of the spiral thermostatic element 30 is secured, preferably by welding, to one leg of a substantially L-shaped switch operating lever 40, the other leg of which is rotatably mounted by means of a single bearing 41 upon the adjusting shaft 27 with the angularly bent arm 42 extending into operative relation with the switch operating pin 11, as shown more clearly in Fig. 2. A switch differential regulating spring 44 is secured at its left-hand end to the operating arm 42 with the right-hand end of the spring 44 biased into engagement with the traveling nut 45 mounted upon the differential adjusting screw 46 which is rotatably mounted in the yoke 47 formed at the end of the arm 42. The improved manner in which the switch operating differential adjustment is obtained is described herein-after in connection with the operation of the thermostatic switch mechanism.

A temperature setting lever 50 is mounted on the adjusting shaft 27 by means of the mounting yoke 51 which carries a clamping screw 52 for securing the adjusting lever 50 in proper position on the shaft 27. An indicating pointer 53 on the lever 50 extends through the arcuate slot 54 formed in the upturned portion 25 of plate 12 and cooperates with the calibrated temperature scale 55 that is adjustably mounted by means of the clamping screw 56 upon the outer face of the upturned portion 25 of the switch mounting plate 12. Thus angular adjustment of the shaft 27 by means of the lever 50 will vary the temperature at which the sensitive thermostatic element 30 operates the sensitive switch 10. The clamping nut 58 holds shaft 27 in its adjusted angular position in socket 26 by cooperating with shoulder 59.

In the improved sensitive control switch unit structure 10 illustrated in Figs. 3 and 4, the removable enclosing cover 10a carrying the mounting bosses 14 and 15 and the switch operating pin 11 has a dust-tight peripheral engagement with the switch terminal and mounting base 61 that also preferably is formed of suitable moulded insulating material. The base 61 carries a current conducting switch terminal strip 62 with a current conducting spring pivot yoke 63 secured to one end thereof by means of the common mounting rivet 64 and with the switch terminal screw 66 in threaded engagement with the other end thereof.

Each of the upstanding arms 67 of the spring yoke 63 is provided with a specially formed dimple 68, preferably of a complementary rounded conical shape as shown in Fig. 5, for receiving in spring pressed pivotal current conducting relation therein a corresponding one of the rounded conically shaped mounting pins 69 extending from the opposite sides of the balanced switch

operating lever 70. The lever 70 is specially shaped at its ends and the two pivot pins 69 are specially located centrally of lever 70 so that the pivot axis 69a extends substantially through the center of gravity of the switch operating lever 70 together with all the switch operating parts carried thereby. Thus the switch operating lever system is statically balanced in all operating positions independently of the particular position in which the switch 10 may be mounted.

As shown in Fig. 5, the rounded conical dimples 68 are provided with a slightly wider internal angle than the external angle of the complementary rounded conical pivots 69 so as to obtain a narrow, annular, self-adjusting bearing and current conducting contact therebetween closely encircling the pivot axis 69a as indicated by the dotted line C in Fig. 5. Moreover, these pivot angles and the opposing biasing forces exerted by the two arms 67 of the spring mounting yoke are so proportioned that both good current conducting contact pressure and automatic compensation for any slight wear occurring in the pivotal mounting are obtained. The resulting improved opposing spring biased pivotal switch mounting possesses yielding, self-adjusting, shock-resisting characteristics that materially increase the operating life of the switch and also maintains the bearing friction that might interfere with the sensitivity and accuracy of control at a minimum value. This improved spring biased pivotal mounting arrangement permits the maximum amount of current to be conducted from the switch terminal strip 62 through the spring yoke 63 to the balanced switch operating member 70 without over-heating and without the use of any flexible current conducting leads or shunts.

The balanced switch operating lever 70 preferably is formed of magnetic material so that it can cooperate with a small permanent magnet 74, preferably of sintered or cast form, to provide snap action operation of the switch. As shown, magnet 74 is mounted in attractive relation with the left-hand end of the operating lever 70 in a recess 76 formed in the base 61 with its distance from and hence its magnetic pull on the lever adjustable by means of the spring 75 and the adjusting screw 71. The snap action tilting movement of lever 70 towards and away from the magnet 74 is limited by means of the adjustable stops 80 and 81 which are threaded directly into the current conducting plate 62 and engage, respectively, with the lower and upper side of the right-hand end of the pivoted member 70. The stop 81 and the pivoted operating member 70 preferably are silver plated so as to provide upon engagement thereof a good current conducting shunt path for diverting current from the pivot bearings 68 and 69 and thereby reducing the current heating effect at the bearings, and increasing the effective life of the switch structure. Also the current conducting yoke 67 preferably is silver plated so that the plating in dimples 68 will cooperate with the plating on pivots 69 to provide a good current conducting wear resisting pivotal bearing thereby insuring a long operating life.

The balanced operating lever 70 carries the movable switch contact 83 that cooperates with the stationary switch contact 84 in opening and closing the circuit connected to the switch terminals 66 and 91, the latter being connected to stationary contact 84 by rivet 92. The switch contacts operate in accordance with the present in-

vention in a special relationship such that circuit making and breaking contact occurs therebetween substantially in the plane of the pivot axis 69a of the balanced operating lever 70 and relatively close to the axis with a substantially minimum relative movement between the contacts and a corresponding minimum tilting movement of the balanced operating lever 70. Also, both circuit making and breaking contact occurs substantially within the confines of a hole or aperture 85 provided in the magnetic material of lever 70 with the magnetic material closely surrounding the switch contacts. In addition, substantially a maximum constant preset pressure is resiliently applied to hold the movable contact 83 in circuit closing contact with the stationary contact 84 with the closing contact pressure applied in a direction that is substantially normal to the plane of the pivot axis 69a. Furthermore, the contact closing pressure is specially proportioned with respect to the snap action provided by magnet 74 so that a relatively slow motion short hammer blow by lever 70 is obtained in the separation of the movable contact 83 from the stationary contact 84. In this way the snap action of the balanced operating lever 70 is specially regulated in its transmission to the movable switch contact 83 so that the maximum current making and breaking capacity is obtained with a minimum relative movement of the contacts and a corresponding minimum tilting movement of the operating lever.

In the improved switch structure, the movable switch contact 83 is carried near the pivot axis 69a at one end of the resilient spring 86 which is secured at the other end thereof remote from the pivot axis to the bendable ear 87 pressed out from the operating member 70. As shown more clearly in Fig. 4, the spring 86 is provided with a central looped portion 87 of substantially the same cross sectional area as the mounting portion 88 in order to allow the operating spring 93 to pass therethrough and still maintain a constant spring pressure gradient. However, the contact carrying end portion 89 of the spring is channel shaped so as to resist deformation, and a slight depression 90 is formed at the end of the spring 86 to provide a definite seat for the spring on the operating lever 70. Thus by bending the ear 87, the maximum preset biasing force with which the end of the contact carrying spring 86 is biased into engagement with the balanced operating lever 70 can be accurately proportioned so as to provide a substantially constant maximum contact closing pressure with a relatively low snap action force provided by magnet 74 as pointed out hereinafter.

Tilting movement of the balance switch operating lever 70 is produced in both circuit opening and circuit closing operation by varying the force of the operating spring 93 which is interposed between the switch operating pin 11 and the balanced switch operating lever 70. The operating spring 93 extends through the looped portion 87 of the contact mounting spring 86 and is secured, preferably by welding, at its end to an adjustable mounting ear 94 pressed out from the lever 70. The force gradient of operating spring 93 is proportioned with respect to the snap action force provided by magnet 74 and the contact pressure provided by spring 86 in such a manner that the resultant accelerating force applied to tilt the balanced lever 70 about its pivot axis 69a through the limited distance between the stops 80 and 81 is maintained at a relatively low value. In

this way the magnetic snap action of the switch operating lever 70 is regulated to produce relatively slow motion of the movable contact 83 in both opening and closing the circuit, as will be pointed out more fully in the following description of the switch operation.

Operation

The improved sensitive thermostatic control switch shown in Figs. 1 and 2 may be arranged to be responsive to the variations in any suitable temperature condition, and the switch terminals connected in any suitable control circuit. However, the improved switch is particularly adapted to serve as a boiler aquastat to stop and start a burner motor in order to maintain the boiler water at a desired temperature, or as a limit switch to stop operation of the burner motor when the boiler water has reached a maximum safe temperature. But it will be evident that the improved thermostatically operated switch of the present invention is not necessarily limited to such service but may be used wherever accurate and sensitive thermostatic control of a control circuit is desired. Also, it will be evident that the improved sensitive switch structure need not necessarily be operated by a sensitive temperature responsive device, but is equally advantageous in case the arm 42 is arranged to be operated by any other sensitive, condition responsive element having only a relatively feeble operating force such as a humidity responsive element, a pressure responsive element, sensitive electrical responsive element or the like.

When the improved temperature responsive switch illustrated is employed in boiler water temperature control service, any increase in temperature of the boiler water will be communicated through the tube 32 to the spiral thermostatic operating element 30. This element will warp so as to rotate the member 40 about the shaft 27 in the clockwise direction (Fig. 2) and thereby move the arm 42 towards the switch operating pin 11 as the temperature increases. The differential spring 44 will first engage with the rounded end of the pin 11. But the force gradient of spring 44 is so proportioned that it is not strong enough to effect a circuit opening operation of the switch contacts 83 until the spring 44 has yielded and moved away from the adjustable stop 45 and into engagement with the arm 42 which serves as a fixed stop for limiting the maximum strain of spring 44. Thereupon the increased force exerted by the thermostatic element 30 is transmitted directly from the arm 42 through the spring 44 in its maximum strain limit position to the pin 11 and thence through the spring 93 to the switch operating lever 70. When the force of spring 93 has been thus increased sufficiently to slightly exceed the pull exerted by magnet 74 that holds lever 70 against stop 81, then a slight accelerating force is available to start rotation of the balanced operating lever 70 about its pivot axis 69a.

With the lever 70 thus started in motion, it strikes the seat 90 of spring 86 with a short hammer blow which ordinarily is sufficient to break any welding that may have occurred between the contacts 83 and 84. As the pivoted lever 70 moves away from the magnet 74, the attractive pull therebetween inherently decreases at a rate determined by the adjustment of screw 77. As soon as the contact pressure spring 86 becomes seated on lever 70, it no longer exerts any force opposing the pull of the magnet. Since

the accelerating force of spring 86 is no longer added to that of spring 93, there is a sharp decrease in the spring force tending to accelerate the contact opening movement of the pivoted lever 70. As a result, a relatively slow opening movement of switch contact 83 is produced after the initial short hammer blow. This resulting slow switch opening movement is of material advantage in interrupting the maximum amount of electrical energy in an alternating current control circuit. Due to the slow opening movement, the length of any arc drawn between the contacts 83 and 84 is held to a minimum until the alternating current passes through the zero value. Thereupon the cooling action of the contacts and the surrounding metal parts of the operating member 70 at the edge of the opening 85 tends to condense any conductive vapors created by the arc so rapidly that arcing is not readily reestablished during the succeeding cycle of the alternating current. The improved circuit interrupting action provided by the improved switch structure of the present invention is so effective that exceptionally high values of current can be successfully interrupted.

The magnetic action set up in the magnetic material of lever 70 surrounding the hole or aperture 85 by the flow of relatively high currents through the switch contacts contributes to the effectiveness of the circuit interrupting action. Since the current flowing in the contact pressure spring 86 is at right angles to the current flowing through the contact 84 and rivet 92 to the terminal 81, magnetic material of the operating arm 70 is interposed between and subject to both the resulting magnetic fields. This concentrates the strongest magnetic field at the periphery of the hole 85 closely surrounding any arc formed between the switch contacts 83 and 84. But with the resulting magnetic fields at right angles there is little if any tendency for the switch contacts to be separated by magnetic repulsion action when relatively high values of current flow either in making or breaking the circuit.

Due to the concentrated magnetic field and the rapid vapor condensing action at the edge of opening 85, contact 83 need be separated from contact 84 only a relatively slight amount to interrupt exceptionally high values of current, for example 4 or 5 mills. Consequently, only a relatively slight pivotal movement of the switch operating lever 70 between the stops 80 and 81 is required to separate the switch contacts. Thus, the variation in magnetic pull exerted by magnet 74 on the pivoted lever 70 that determines the operating differential of the switch unit itself can be maintained relatively small with the switch contact closing pressure automatically balancing a substantial part thereof. This combination enables very sensitive and accurate control of a switch of relatively high current capacity to be obtained with a relatively feeble operating force.

To effect the operation of the switch from the open position to the closed position, the temperature to which the thermostatic element 38 is responsive must decrease. Thereupon, the operating arm 42 is moved away from the switch operating pin 11. But the differential regulating spring 44 still exerts a large enough force upon the pin 11 to maintain spring 93 stressed sufficiently to oppose the reduced pull of magnet 74 that holds the switch operating lever 70 against stop 80. When the spring 44 engages with the differential adjusting nut 45 that limits the re-

lease of the strain of spring 44 the operating pin 11 can then travel along with the operating arm 42. In this way, the adjustment of nut 45 varies the temperature operating differential of the switch. When the stress in the switch operating spring 93 has thus been relieved sufficiently so that the reduced pull of the magnet 74 exceeds the force of the spring 86, then the unbalanced magnetic pull becomes available to start acceleration of the switch operating member 70 away from stop 80 in the circuit closing direction. As soon as the movable contact 83 engages the stationary contact 84, the maximum preset biasing force of the contact pressure spring 86 at once becomes effective to resiliently hold contact 83 in engagement with contact 84 so as to prevent rebound or chattering. Since the maximum preset biasing force of spring 86 is applied normally to the plane through the pivot axis 69a and the face of stationary contact 84, there is no tendency for contact 83 to slide upon contact 84. This materially reduces the chances for any appreciable welding to occur in closing the switch contacts with high inrush current values such as are likely to occur in inductive alternating current circuits. Also this helps to maintain the operating differential of the switch relatively constant.

As the switch contacts close, the increasing pull of magnet 74 on lever 70 is opposed by both the preset biasing force of spring 86 and also the increasing stress built up in spring 93. As a result, the continued pivotal movement of the switch operating member 70 into engagement with stop 81 is materially slowed up so that final rebounding and chattering of the moving switch parts are minimized.

Upon closing the switch, the engagement of the right-hand end of operating member 70 with the head of the stop screw 81 establishes a good conducting path in shunt with the pivot bearings for diverting a substantial part of the current in the circuit controlled by the switch from the bearings. Thus the pivot bearings carry the total current only momentarily.

In case any substantial welding of the switch contacts should occur, when the operating pin 11 is depressed by operation of the arm 42 as previously described, the short hammer blow delivered by the pivoted lever 70 may not be sufficient to break the contacts apart. In this case, continued movement of the arm 42 will continue movement of the operating pin 11 to increase the strain set up in spring 93. Finally, as the spring 93 bends, the finger 95 carried thereby is brought into engagement with the end of the pivoted lever 70. In this way the force of the operating arm 42 is transmitted directly through the pin 11 and the finger 95 to the end of the pivoted lever 70, thereby providing an increased force tending to break the switch contacts 83 and 84 apart. The strengthening channel section 89 formed at the end of the contact pressure spring 86 transmits the increased force from the lever 70 to the contact 83.

In the modified form structure shown in Fig. 6, the switch is of the double throw type adapted to break one circuit and make another circuit. The general features of construction of the enclosing casing, the magnet mounting and adjusting mechanism, and also the improved spring biased pivot mounting shown in Fig. 5 for the movable switch parts are substantially the same as those described in connection with the single throw switch of Figs. 3 and 4. However, with

the double throw switch, the special current conducting spring yoke 63 is mounted centrally of the switch base 61a so as to receive the pair of mounting pivot pins 69 that extend centrally from the opposite sides of the balanced pivoted switch operating lever 70a. The permanent magnets 74 and 74a are mounted in magnetic attractive relation with the opposite ends of the lever 70a. A contact pressure spring 101 has one end thereof secured, preferably by welding, to the slotted ear 116 at the end of the pivoted lever 70a which may be bent so that the contact 102 is carried at the other end of spring 101 in a hole or aperture 103 formed in the lever 70a with a preset contact closing pressure in cooperating circuit controlling relation with the stationary contact 104 to which the switch terminal 105 is connected. Similarly, the contact pressure spring 106 is adjustably secured at the opposite end of the lever 70a and carries the movable contact 107 in the opening 108 formed in lever 70a in cooperating circuit controlling relation with the stationary contact 109 to which the switch terminal 110 is connected.

The pivoted lever 70a carries centrally thereof the mounting rivet 111 to which the bow spring 112 is secured at substantially its center, preferably by welding, with one end of the bow spring 112 in operative relation with the operating pin 11 and the other end in operative relation with the adjusting screw 113.

As shown, the operating pin 11 has been depressed so as to set up a strain in the right-hand end of the spring 112 sufficient to tilt the pivoted lever 70a out of attractive relation with the left-hand magnet 74 and into attractive relation with the right-hand magnet 74a, and at the same time set up a strain in the left-hand part of the bow spring 112 sufficient to return the pivoted lever 70a, to its initial position when the force operating the pin 11 is removed. During the tilting movement of the lever 70a, contact 102 is separated from the contact 104 with a short hammer blow in substantially the same manner as described in the separation of the contacts of the switch of Figs. 3 and 4 to obtain high current interrupting ability with a minimum movement of the switch operating pin 11.

Likewise, during the final tilting movement of the pivoted lever 70a, the contact 107 is brought into engagement with the contact 108 in substantially the same manner described in connection with the switch in Figs. 3 and 4 without rebounding, chattering or liability of welding of the switch contacts for exactly the same reasons as previously pointed out.

Upon the release of the operating force impressed upon the operating pin 11, the strain set up in the left-hand part of bow spring 112 becomes effective to return the pivoted member 70a to its initial biased position. In the initial part of this return tilting movement of lever 70a, the contact 107 is separated from the stationary contact 108 with a short hammer blow and continued slow motion to provide the high current circuit interrupting capacity previously described. Subsequently the contacts 102 and 104 are engaged in the manner described.

The double throw switch shown in Figs. 6 and 7 is provided with three terminal connecting screws 115, 116, and 117 which are connected respectively to the spring pivot yoke 63, the stationary switch contact 104 and the stationary switch contact 109. Thus the switch may be employed in the ordinary form of 3-wire control

circuit and operated by the sensitive thermostatic element 30 of Figs. 1 and 2 or by other suitable condition responsive means.

The tilting movement of the pivoted switch lever 70a is limited by the adjustable screw stops 118 and 119, the former limiting the tilting movement towards the left-hand magnet 74 and the latter limiting the tilting movement towards the right-hand magnet 74a. The stop 118 is threaded into the specially formed conducting plate 122 which is connected by the conducting rivet 123 with the central switch terminal and also is connected by the rivet 125 with the spring pivot yoke 63. Thus a good conducting shunt around the spring pivot bearings is established upon the engagement of the lever 70a with the stop 118. Similarly, the stop 119 is threaded into plate 122 so as to establish a good conducting shunt around the pivot bearings when the lever 70a engages therewith.

What I claim as new and desire to secure by Letters Patent of the United States is:

1. A sensitive temperature responsive switch comprising in combination, a substantially balanced switch operating lever, a switch contact movably mounted on said lever and having preset contact closing pressure means, spring pivot means for mounting said lever and conducting current through said lever to said movable contact, a stationary contact cooperating with said movable contact to control a circuit, a current conducting stop for said lever connected in said circuit in shunt with said spring pivot means upon operation of said lever to close said circuit, variable spring means for biasing said lever to operate said movable contact from the circuit closing position to the circuit opening position, magnetic means for variably opposing the combined biasing action of said spring means and said contact closing pressure means to effect a regulated snap action movement of said lever in operating said movable contact each way between said circuit controlling positions and for biasing said lever to operate said movable contact to the circuit closing position, temperature responsive means having a movable operating member for varying said spring biasing means to effect operation of said lever, and an auxiliary spring biasing means movable with said operating member and interposed between said member and said spring biasing means and provided with an adjustable stop carried by said operating member for regulating the operating temperature differential of said lever.

2. In combination, a movable current conducting switch member having spring pivot current conducting mounting means and a current conducting stop in shunt therewith, variable spring means for biasing said member away from said stop, magnetic biasing means for variably opposing the biasing action of said spring means to effect snap action movement of said switch member away from said stop and for biasing said switch member to engage said stop with a snap action upon predominance thereof over said spring biasing means, and temperature responsive switch operating means having a movable operating member for varying said spring biasing means and provided with an adjustable biasing means for maintaining said spring biasing means predominant over said magnetic biasing means during a variable movement of said operating member to regulate the operating differential of said switch member.

3. In combination, a movable switch member,

magnetic means for biasing said member from one circuit controlling position to another circuit controlling position, variable spring biasing means for variably opposing the biasing action of said magnetic means to effect snap action movement of said switch member each way between said circuit controlling positions, and condition responsive switch operating means having a movable member and an auxiliary biasing spring mounted on said member for varying said variable spring biasing means and provided with a fixed stop for limiting the maximum strain of said auxiliary biasing spring and adjustable stop for limiting the release of said strain to regulate the operating differential of said switch member.

4. In combination, a movable switch member, variable biasing means for biasing said member from one circuit controlling position to another circuit controlling position, cooperating biasing means for variably opposing the biasing action of said first biasing means to effect snap action movement of said switch member each way between said circuit controlling positions and for biasing said member to said other circuit controlling position upon a predetermined variation of said first biasing means, and condition responsive means having a movable member and an auxiliary biasing spring mounted on said member for varying said first biasing means and provided with a fixed stop for limiting the maximum strain of said auxiliary biasing spring and an adjustable stop for limiting the release of said strain to regulate the operating differential of said switch member.

5. In combination, a snap action switch biased to one circuit controlling position, and condition responsive means having a movable member and an auxiliary biasing spring mounted on said member for operating said switch to another circuit controlling position and provided with a fixed stop for limiting the maximum strain of said auxiliary biasing spring and an adjustable stop for limiting the release of said strain to regulate the operating differential of said switch.

6. A thermostatic switch comprising in combination, a snap action switch biased to one circuit controlling position, a mounting bracket therefor provided with annular mounting means for varying the angular position of said bracket, a tube closed at one end and having means at the open end thereof for mounting said tube in a wall and for supporting said annular mounting means in axial alignment with said tube, a shaft extending axially through said annular mounting means with one end thereof rotatably mounted in said closed end of said tube and having adjustable mounting means for securing said shaft to said bracket in different angular positions, a substantially L-shaped switch operating lever having one leg rotatably mounted on said shaft and provided with a biasing spring having an adjustable stop for regulating the operating differential of said switch unit with the other leg extending through said annular mounting means into said tube, and a spiral bimetallic operating element surrounding said shaft and having one end thereof secured adjacent the said one end of said shaft and the other end thereof secured to said switch operating lever for operating said switch in accordance with variations in the temperature of said element from a value determined by the angular adjustment of said shaft.

7. In combination, a switch provided with mounting means having an opening therein, a tube closed at one end and having means at the

open end thereof for mounting said tube in a wall and for supporting said switch in different angular positions with said opening in alignment with said tube, a shaft extending through said opening with one end thereof inside said tube and having adjustable mounting means for varying the angular position of said shaft, a substantially L-shaped switch operating lever having one leg rotatably mounted on said shaft with the other leg extending through said opening into said tube, and a spiral bimetallic element having one end thereof mounted adjacent the said one end of said shaft and the other end thereof secured to said switch operating lever for operating said switch in accordance with variations in the temperature of said element.

8. In combination, a switch having annular mounting means, a shaft extending axially through said annular mounting means, a substantially L-shaped switch operating lever having one leg thereof rotatably mounted on said shaft with the other leg extending through said annular mounting means, and a spiral bimetallic operating element having one end secured to said shaft and the other end secured to said lever.

9. In a switch, in combination, a substantially balanced magnetic operating lever having rounded conical pivots extending from opposite sides thereof with an opening in said lever adjacent the pivot axis and provided with a bendable ear remote from said axis, a contact closing pressure spring having a switch contact at one end thereof and the other end thereof secured to said bendable ear for movably supporting said contact in said opening with said spring biased to provide a preset contact closing pressure normal to the plane through said axis and the face of said contact, a current conducting spring yoke provided with a complementary rounded conical shaped dimple in each arm thereof for receiving in spring pressed pivotal current conducting relation therein a corresponding one of said pivots, a stationary switch contact cooperating with said movable contact to make and break a circuit in said plane, a magnet in attractive relation with one end of said lever for biasing said lever to operate said movable contact to the circuit closing position, an operating spring cooperating with said preset contact closing pressure spring for variably opposing the biasing action of said magnet to effect a regulated snap action movement of said lever in opening and closing the circuit and for biasing said lever to operate said movable contact to the circuit opening position, and a current conducting stop for engaging the other end of said lever to shunt said current conducting pivots upon snap action operation of said lever to close said contacts.

10. In a switch, in combination, a switch operating lever having opposite rounded conical pivots, a movable switch contact mounted on said lever, a current conducting spring yoke provided with a complementary rounded conical shaped dimple in each arm thereof for receiving in spring pressed pivotal current conducting relation therein a corresponding one of said pivots, a stationary switch contact cooperating with said movable contact to control a circuit, and a current conducting stop for engaging said lever to shunt said current conducting pivots upon operation of said lever to close said contacts.

11. In a switch, in combination, a switch operating lever having opposite mounting pivots, a

switch contact mounted on said lever, a current conducting spring yoke provided with a complementary dimple in each arm thereof for receiving in spring pressed pivotal current conducting relation therein a corresponding one of said pivots, a stationary switch contact cooperating with said movable contact to control a circuit, means for effecting snap action pivotal movement of said lever in opening and closing the circuit, and a current conducting stop for engaging said lever to shunt said current conducting pivots upon snap action operation of said lever to close said contacts.

12. In a switch, in combination, a magnetic switch operating lever having opposite pivotal mounting means and an opening in said lever adjacent the pivot axis, a switch contact having means for mounting said contact on said lever in said opening with a preset contact closing pressure, a current conducting spring yoke provided with complementary pivotal mounting means in the arms thereof for establishing spring pressed pivotal current conducting relation with said opposite pivotal mounting means, a stationary switch contact cooperating with said movable contact in said opening to provide a magnetic field in making and breaking a circuit, opposing biasing means for effecting a regulated snap action movement of said lever in opening and closing the circuit, and a current conducting stop for engaging said lever to shunt said current conducting pivotal mounting means upon operation of said lever to close said circuit.

13. In a switch, in combination, a switch operating lever, a movable switch contact resiliently mounted on said lever, spring pivot means for mounting said lever and conducting current through said lever to said movable switch contact, a stationary switch contact cooperating with said movable contact to control a circuit, and a current conducting stop for said lever connected in shunt with said spring pivot means upon operation of said lever to close said circuit.

14. In a switch, in combination, a substantially balanced pivoted operating lever, a movable switch contact, a spring for mounting said contact on said lever to provide a preset contact closing pressure normal to a plane through the pivot axis and the face of said contact, a stationary switch contact cooperating with said movable contact to make and break a circuit in said plane, and biasing means for effecting a slow motion hammer blow of said lever on said spring in opening the circuit.

15. In a switch, in combination, a substantially balanced pivoted magnetic operating lever having an opening therein, a switch contact movably mounted on said lever in said opening and having biasing means for providing a preset contact closing pressure normal to a plane through the pivot axis and the face of said contact, a stationary switch contact cooperating with said movable contact to make and break a circuit in said plane, and snap action means including a magnet and an opposing spring cooperating with said contact biasing means to effect a slow motion hammer blow of said lever on said movable contact in breaking the circuit.
16. In combination, a control member movable between two control positions, a variable biasing means for biasing said member to move from one of said positions to the other, an opposing variable biasing means effective upon predominance thereof over said first biasing means for biasing said member to move from said other position to said one position, and condition responsive means having a pair of relatively movable operating members movable as a unit upon response of said condition responsive means to variation of the condition to one value for varying said second biasing means into predominance over said first biasing means and having relative movement therebetween upon response of said condition responsive means to opposite variation of the condition to another value for oppositely varying said second biasing means out of predominance over said first biasing means, and provided with an adjustable stop for controlling the relative movement between said members to determine said other value.
17. In combination, a control member movable between two control positions, opposing variable biasing means therefor, and condition responsive means having a pair of relatively movable operating members movable as a unit for varying one of said biasing means into predominance over the other and thereby biasing said control member to move from one of said positions to the other, and provided with an adjustable stop for controlling the relative movement between said operating members for varying said one biasing means out of predominance over the other and thereby bias said control member to move from said other position to said one position.

JOHN E. LAKE.
